United States Patent Office

Des. 183,121
Patented July 1, 1958

183,121

SPACE CONDITION RESPONSIVE INSTRUMENT

Henry Dreyfuss, South Pasadena, Calif., assignor to Minneapolis-Honeywell Regulator Company, Minneapolis, Minn., a corporation of Delaware

Application July 15, 1957, Serial No. 46,938

Term of patent 14 years

(Cl. D52—7)

FIG. 1

FIG. 2

Figure 1 is a front perspective view of a space condition responsive instrument embodying my new design, and;

Figure 2 is a side elevation view of the space condition responsive instrument shown in Figure 1.

The dominant features of the design reside in the solid line portions.

I claim:

The ornamental design for a space condition responsive instrument, as shown and described.
